UNITED STATES PATENT OFFICE.

CLIVE W. LANPHERE, OF NEW YORK, N. Y.

UNIVERSAL JIMMYPFOOF AUTOMATIC LOCK.

Application filed November 28, 1923. Serial No. 677,358.

This invention relates to improvements in locks, and, more particularly, to an automatic lock having a plurality of bolts adapted to be projected into locking engagement with a keeper when a door is closed.

An object of my invention is to provide an automatic lock which embodies a plurality of bolts.

Another object of my invention is to provide a lock having a plurality of bolts which may be engaged with a keeper in such a manner as to prevent the separation of the bolts from the keeper by the action of a jimmy.

A further object of my invention is to provide a lock having a main bolt carrying an auxiliary bolt which latter is adapted to cooperate with a keeper and the main bolt in such manner as to prevent the main bolt from being withdrawn from the keeper without the appropriate instrumentalities.

Another object of my invention is to provide a lock having a plurality of bolts which are operated sequentially to engage a keeper.

Another object of my invention is to provide a lock having a plurality of bolts which are operated wholly automatically.

Another object of my invention is to provide a lock having a plurality of bolts which may be operated automatically or manually.

Another object of my invention is to provide a lock having a plurality of bolts and locking means for said bolts which are operated automatically.

Another object of my invention is to provide a rigid lock having a plurality of bolts so operated in cooperation with a keeper that when engaged therewith the lock will resist the action of a jimmy.

Another object of my invention is to provide a lock which possesses great strength and yet is simple in its construction and operation.

Further objects of the invention will appear as the description is read.

Briefly stated, the invention is embodied in the form of a casing having a plurality of bolts mounted therein for projection to and from the casing. This bolt consists of a main bolt, which may be termed a carrier bolt, and a pair of projecting prongs or tongues which engage with a keeper when the bolt is fully projected. Within the main bolt is slidably disposed an auxiliary bolt which also carries a projecting tongue adapted to bridge the space between the pro-

jecting tongues or to project vertically or at right angles from the projecting portion of the main or carrier bolt. The keeper is so designed that the auxiliary bolt engages behind a bar thereof so as to prevent retraction

of the main bolt. An additional means may be provided to prevent retraction of the bolt and may comprise a projection on the auxiliary bolt adapted to be positioned to engage with another rigid projection which

may be made integral with the casing. The main bolt is automatically projected upon engagement of a releaser bar with the keeper upon closing of the door upon which the lock is mounted.

When the main bolt is fully projected, the auxiliary bolt is then operated, also automatically to engage behind the keeper as above described. The auxiliary bolt is retained in this position and the lock is also provided with interlocking means

for locking the auxiliary bolt as well as the main bolt in their unlocked or retracted positions. Although the lock is automatic, the operating mechanism is so arranged that

manual operation of the bolt may be had, if desired. The operating mechanism is of simple design and the bolts are of a very rigid nature, thus providing a lock which is capable of resisting great force which may be applied through the action of a jimmy or

otherwise.

The invention may be better understood by referring to the accompanying description and drawings in which latter—

Fig. 1 is a side elevational view of my lock with a sideplate removed.

Fig. 2 is a transverse section taken on line II—II, in Fig. 1.

Fig. 3 is a view similar to Fig. 1 and shows certain of the operating parts in different positions.

Fig. 4 is a fragmentary view taken on line IV—IV, in Fig. 3.

Fig. 5 is a transverse section taken on line V—V, in Fig. 4.

Fig. 6 is a perspective view of the main bolt of my lock on a slightly enlarged scale and shows the auxiliary bolt in its projected position.

Fig. 7 is a side elevation of a modification of my lock in which the main bolt has no extension to receive the end of the lock bar, and

Fig. 8 is a modified form of the releaser mechanism.

An embodiment of the invention may in-

clude a housing or casing 15 having a reciprocable locking-member or bolt 16 in the form of a dead or main bolt 16. A cover plate 20 may be provided and screwed to the 5 casing by suitable screws. The bolt 16 may be slideable on the inner surface of a wall 17, and between walls 18 and 19 of the casing, which serves as guide members.

Means in the form of compression springs 10 21 and 22 are provided to exert a force to project the bolt from the casing. The springs may be positioned upon posts 23 and 24 attached to a wall 25 of the casing and the ends of the springs may be disposed in apertures 15 26 and 27, respectively, in an inner end of the bolt 16. Other obvious methods of disposing the springs in the bolt may be provided. The opposite end of the bolt 16 may be projectable from the casing into operable 20 relation with a keeper or guard 28. In the present invention the said bolt end is bifurcated and the tines or projections 29 and 31 thereof are spaced apart a suitable distance to permit the entrance of a substantial 25 portion 32 of the keeper therebetween when the projections are thrust into apertures 33 and 34, respectively, in the keeper upon a projection of the bolt 16 to its operative position.

30 When the bolt has been projected, means are provided to secure the keeper and bolt in locked engagement in opposition to a force which may be applied to separate the keeper from its operative relation with the lock, as, 35 for example, when a "jimmy" is employed.

The means just-mentioned may comprise an auxiliary bolt 35 carried by the bolt 16 and may be reciprocably mounted within the bolt 16, the latter being termed a main or 40 carrier bolt.

45 For the purpose of facilitating the description, the lock may be considered as being in its normal operative position in a door. Thus the movement of the main bolt 16 may be considered as horizontal and the movement of the auxiliary bolt 35 as vertical.

50 As more clearly shown in Fig. 6 the auxiliary bolt may comprise a body portion having an extension 36 with a cross or lock-bar 55 37 vertically disposed adjacent to the projecting end thereof. As stated, the auxiliary bolt 35 is movable within the main bolt which latter may be provided with a suitably shaped aperture 38 (see Fig. 5) to provide a 55 sliding fit for the body of the auxiliary bolt 35. The aperture 38 may extend into the projections 29 and 31 and the lock bar 37 may, when in its lower position, be completely encased within the main bolt 16. The auxiliary bolt is constantly urged to move to its upper position as shown in Fig. 3 under the action of springs 39 and 41, positioned between the ends of sockets 42 and 43 in the auxiliary bolt 35 and the bottom of the aperture 38. Posts 44 and 45, secured to the bot-

tom of the aperture 38 may be provided as guides for the springs. The auxiliary bolt is adapted to slide vertically by reason of guides 39 integral therewith, which fit grooves 40 in the main bolt. The auxiliary 70 bolt is, however, retained from upward movement, when the main bolt is within the casing, but is arranged to take its upper position in timed relation to the entrance of the main bolt into the apertures 33 and 34 75 of the keeper or guard 28. Means for retaining the auxiliary bolt in its upper position may comprise a latch 46 of right-angle form, as shown, which may be slidably positioned in a slot 47 in the main bolt. A flat spring 80 48 may be arranged to normally urge the latch 46 to move an end 49 thereof toward the auxiliary bolt 35 which is provided with a notch 51 so positioned that when the auxiliary bolt reaches its upper position the end 85 49 of the latch enters the notch and locks the auxiliary bolt in position. The latch may be disengaged from engagement with the auxiliary bolt by means to be presently described.

It will be understood that the auxiliary 90 bolt 35 takes its upper position when the main bolt 16 is in its projected position at which time a retainer bar 52 occupies a recess 53 in the auxiliary bolt. The recess 53 is formed at one side of the auxiliary bolt 35 95 and, in conjunction with an inner surface 54 of the main bolt 16 (see Fig. 5), constitutes an elongated aperture for the reception of the retainer bar 52. This bar is movable sidewise in one direction under the action of a spring 55 disposed between a projection 56 secured to the upper side of the main bolt 16 and an offset end 57 (see Fig. 5) of the bar 52 which end is slideable in a guide 58 and adapted to be engaged by a wall 59 of the casing and a face plate 60 as the main bolt 16 is moved outwardly. When the main bolt is retracted, means operate to first depress the auxiliary bolt 35 and when this latter bolt reaches its lower position it is retained in such position by the latch 57 as the main bolt 16 is retracted. The end 57 of the retainer bar 52 is, therefore, moved away from the face plate 59 and as the auxiliary bolt moves downwardly the retainer bar 52 becomes disposed upon the upper edge 110 of the auxiliary bolt 35, as shown in Fig. 1.

An important feature of the present invention consists in means for automatically effecting an actuation of the lock mechanism 115 to project the main bolt 16 and throw the auxiliary bolt 35.

As above described, the main bolt 16 is normally urged toward its projected position by means of the potential energy of the 120 springs 22 and 23, which are placed under compression when the said bolt is retracted. Means for holding or detaining the bolt 16 in its retracted position may comprise a bolt tumbler 61 adapted to engage with a groove 125 130

62 disposed transversely of the bolt 16. The tumbler 61 may include a slide rod 63 movable in a guide 64, a guide 65 being provided to confine the movement of the tumbler 5 which is normally urged toward the bolt 16 by reason of the expansion action of a spring 66 positioned between a shoulder 67 on the tumbler and guide 65 secured to the casing. The upper end of the rod 63 may be provided 10 with a cam-finger 68 having a chamfered end 69 so arranged as to engage with a similar end 71 of a releaser bar 72, the opposite end 70 of which normally projects through an aperture 73 in the wall 59 and 15 face plate 60 of the casing.

The releaser bar 72 is slidable in guides 74 and 75 secured to the casing. A spring 76 positioned on the bar 72 between the guide 74 and the enlarged end 70 of the bar 20 exerts a constant force to move the said end, which is of beveled form, out from the casing. The end 70 of the releaser-bar is, therefore, normally projected from the casing and when in this position the chamfered 25 surface of the releaser bar 72 is in contact with the chamfered finger 68 of the bolt tumbler 61, the opposite end of which is positioned in the notch 62 in the main bolt to hold it retracted (see Fig. 1). If desirable 30 the releaser bar may be used as a latch, in which case it would be provided with the usual operating knob.

When the lock is moved with a door to bring the end 70 of the releaser bar 72 in 35 contact with the keeper or guard 28, the releaser is moved inwardly to release the main bolt by disengaging the tumbler therefrom which bolt is projected under the action of the springs 22 and 23 and enters the apertures 33 and 34 in the guard 28. A retraction of the bolt may be effected 40 either by means of a knob 80, the shank 78 of which may be inserted into a socket 79 (see Figs. 2 and 5), or by means of a key inserted 45 into a tumbler cylinder 82 of a key barrel 83 having an arm 84 associated therewith.

Means for cooperating with a knob or key for moving the main bolt 16 may comprise a gear rack 85 integral with the bolt 50 16 and a segment or toothed disk 86 loosely mounted on a shaft 87 (see Fig. 2) journaled in the wall 18 of the casing 15. The shaft may be provided with the above-mentioned socket 79 to receive the shank 78 of 55 a knob 80.

The shaft 87 may project into the casing through the disk 86 and may have a collar or hub 88 secured thereto. The shaft 87 may be provided with an external flange 91 which in conjunction with the hub 88 prevents endwise movement of the shaft. The hub 88 may be secured to the shaft 87 by means of a projection 92 integral with the shaft and disposed in a recess in the hub and 60 65 by screws 93.

The hub 88 may be provided with a relatively long arm 94 for engaging with the auxiliary bolt to depress the same in opposition to the springs 39 and 41 and may be termed a depressor arm. The hub is also 70 provided with a relatively short arm 95 to make contact with and disengage the latch 46 to permit the downward movement of the auxiliary bolt. This arm may be termed 75 a releaser-arm.

It will be understood that both last-mentioned arms are so positioned that a timed co-ordination of the operative elements is effected and the releaser arm releases the auxiliary bolt just prior to the engagement 80 of the depressor arm therewith.

Inasmuch as the segment or toothed disk 86 is loose on the shaft, it may be positioned so that an end tooth 96 is in mesh with the teeth at the inner end of the rack 85 when the main bolt 16 is projected and may remain in this position during a preliminary partial rotation of the hub 88, which rotation may be considered as a lost-motion action. The hub, is, however, normally positioned with the depressor arm 94 in contact with a stop-pin 97 secured to the segment 86 and such contact is maintained through the expansive action of a spring 98 mounted on an arcuate rod 99 secured to the 90 arm 95. The rod 99 is slidable in a guide 101 fastened to the segment 86 which, as above stated, is held from rotation by reason of its engagement with the rack 85.

After the bolt has been projected and a 100 reverse movement is desired, the hub 88 is rotated by means of a key or knob in the direction of the arrow X. The first action of such movement causes the arm 95 to release the auxiliary bolt 35 and a subsequent 105 downward movement of the auxiliary bolt is effected as the depressor arm 94 engages therewith. During the operations just mentioned, the main bolt is not retracted since no force has been applied to the toothed disk 86. A continued movement of the hub 88 however, brings the arm 95 thereof into engagement with a lug 102 mounted on the periphery of the disk 86. It will thus be evident that a rotary movement of the arm 110 115 120 125 130 95 will cause the teeth of the segment 86 to traverse the rack 85 and move the same to retract the main bolt 16, and, as the door carrying the lock is moved away from the keeper, the bolt tumbler 61 will engage with the groove 62 in the bolt 16 and thus retain it in position for automatic projection when the door is again moved to bring the releaser bar 72 into engagement with the keeper 28.

As an additional means of preventing a retraction of the main bolt I may provide the auxiliary bolt with a boss or post 103 (see Fig. 5) and at a suitable point within the casing a projection or stop 104 may be positioned. The stop may be so located that

when the auxiliary bolt ascends, the stop 104 will be disposed in the return path of the bolt 16, thus providing an additional means to prevent inward movement of the bolt 16 until the hub 88 is rotated by a key or knob.

When a key is employed, the key barrel 83 may be so positioned that an arm 84 on the key cylinder thereof is adapted to engage with a pin 108 projecting from the arm 95 and a rotation of the hub 88 may be effected when the key is turned.

It will be evident that by reason of the correlation between the bolt operating mechanism proper and the key-barrel, the main bolt and auxiliary bolt may be actuated either by means of or independently of the knob secured to the shank 78. In the application of the lock construction previously described to a rim lock, a lock barrel may be journaled in the casing and may be connected to the key cylinder by a shank, the barrel having an arm to engage the pin 108.

Means are also provided for temporarily retaining the main bolt and auxiliary bolt 25 inoperative to the action of a key or knob. Such means may comprise a push rod 109 associated with one end 110 of a lever 111 fulcrumed on a pin 112 secured to a wall of the casing. The opposite end 113 of the 30 lever may be engaged with a secondary push rod 114. The rods 109 and 114 may extend through apertures 115 and 116 in the face plates and may be provided with heads or 35 push buttons 117 and 118, respectively.

An end 119 of the push rod 109 is movable into and out from the path of movement of a lug 121 carried by the disk 86. An inward movement of the button 117 may then be effected to position the end 119 of the 40 push rod 109 to interrupt the movement of the disk 86 and consequently prevent an actuation of the main and auxiliary bolts. A disengagement of said rod may be effected by an inward movement of the secondary 45 push rod 114.

The usual additional snap latch 122 may be provided comprising a rod movable between guides 75 and through the guide 74. The snap latch may be arranged to normally have an enlarged beveled end 123 projecting from an aperture 124 in the side 50 and the face plate 60 of the casing. The rod may be movable in the guide 74 and a spring 125 disposed between said guide and the end 123 may serve to normally project the latch bar. The guard may be provided with the usual aperture 126 to receive the end 123 when the lock and guard are in the proper relation as when a door is closed.

Manual means for retracting the latch bar may include a stub-shaft 127 journaled in the casing and provided with a socket 128 to receive the shank of a knob. The shaft 127 may have a lever arm 129 projecting therefrom and adapted to engage with an en-

larged end 131 of the latch 122, whereby an oscillatory movement of the shaft when produced by rotation of the knob will serve to retract said latch. A spring 133 positioned on an arcuate rod 134 secured to the arm 129 acts to return the arm to its initial position for contact with the end 131. The ends of the spring 133 may engage with a guide 135 secured to the casing and with the arm 129. Although an arcuate spring is illustrated for returning the knob barrel, it is obvious that other well-known types of springs may be employed, such, for example, as a leaf-spring. In such case, suitable provision may be readily made by those skilled in the art for adapting the present knob barrel to such a spring.

If desired, the bolt may be projected manually. In such case the knob or key barrel may be turned in a direction opposite to that employed in retracting the bolt 16. Obviously, in reversing the rotation of the key cylinder or knob barrel for manual projection of the bolt 16, the arms 84 or 94, respectively, will engage the pins 108 and 97, respectively.

As shown in Fig. 7, my invention may be practiced by providing a main bolt 136 with a single projecting end 137 from which the lock bar 37 of the auxiliary bolt is projectible. The end 137 of the main bolt 136 may, in this case, pass through an aperture 138 in a keeper 139 and when the lock bar 37 is projected from the main bolt a barrier will be provided against a return of 100 said main bolt until the lock actuating mechanism is properly operated. A catch comprising a head stud 139', slidably mounted in the side of the casing, may be provided for holding the bolt 16 in its retracted position. A projection 140' may be provided on the bolt 16 with which the stud 105 may cooperate. By pushing inwardly on the stud it may be positioned forwardly 110 of the projection on the bolt to hold the latter in its retracted position and also to render the releasing means ineffective.

As illustrated in Fig. 8, the releaser bar 72 and the bolt releasing mechanism actuated thereby may comprise a nose 70 projecting outwardly from the bolt, the latter being movable in guides 74, 75. A spring 76 mounted on the bar between the guides may operate to normally thrust the nose 70 from the casing for engagement with the keeper or guard 28. The inner end 141 of the releaser bar may be provided with a pin 142 disposed in a cam slot 143 of a lever 144 pivoted at 145 in the casing. The lower end of the lever 144 carries a pin 146 engaging in a cam slot 147 at the end of a pawl or tumbler 148 pivoted at 149 in the casing. The pawl or tumbler may engage a member 152, such as a recess in the main bolt 16, and for that purpose may 125 130

be provided with a projection or tooth 151. The operation of the mechanism is obvious.

The rugged character and automatic features, combined with a relative simple construction renders my lock valuable for doors of buildings or entrances in general, and constitutes an important advance in the art.

Although a preferred embodiment of the invention is shown and described herein 10 it is to be understood that modifications may be made therein without departing from the spirit and scope of the invention as set forth in the appended claims.

What is claimed is:—

15 1. A lock comprising a casing, a bolt, means for holding said bolt retracted, means for automatically releasing said means, means for projecting said bolt when released and reciprocal means within said bolt for 20 engaging an external member to prevent retraction of said bolt.

25 2. A lock comprising a casing, a bolt reciprocal within said casing, a keeper, means for holding said bolt retracted, means engaging said keeper for releasing said means, means for automatically projecting said bolt when released into operative relation with 30 said keeper and means within said bolt for engaging said keeper to prevent retraction of said bolt.

35 3. A lock comprising a casing, a bolt reciprocal within said casing, a keeper, means for holding said bolt retracted, means engaging said keeper for releasing said means, means for moving said bolt automatically when released into operative relation with said keeper, a member movable within said bolt and disposed transversely of said bolt for engaging said keeper to 40 prevent retraction of said bolt.

45 4. A lock comprising a casing, a bolt reciprocal horizontally within said casing, a keeper, means for holding said bolt retracted, means engaging said keeper for releasing said means, automatic means for moving said bolt when released into operative relation with said keeper, a member within said bolt and wholly movable vertically to engage said keeper and prevent 50 retraction of said bolt.

55 5. A lock comprising a casing, a bolt movable in said casing, a keeper, means for holding said bolt retracted, means engaging said keeper for releasing said means, a member mounted on said bolt for engaging said keeper to prevent retraction of said bolt, and means for automatically moving said bolt and said member when said bolt is released.

60 6. A lock comprising a casing, a bolt movable within said casing, an external member, means for holding said bolt retracted, means engaging a keeper for releasing said means, means for automatically projecting said bolt when released into operative relation with said external member, and a movable 65

member carried by said bolt and movable relative thereto for engagement with said external member to prevent a retraction of said bolt.

7. A lock comprising a casing, a bolt, 70 means for holding said bolt retracted, means for automatically releasing said means, automatic means for projecting said bolt when released, means within said bolt for engaging an external member to prevent retraction of said bolt and means for retracting said bolt.

75 8. A lock comprising a casing, a bolt reciprocal within said casing, a keeper, automatic means for holding said bolt retracted, 80 means engaging said keeper for releasing said means, means for moving said bolt when released into operative relation with said keeper, means within said bolt for engaging said keeper to prevent retraction of 85 said bolt, and means for disengaging said engaging means and for retracting said bolt.

9. A lock comprising a casing, a bolt reciprocal within said casing, a keeper, means for holding said bolt retracted, means 90 engaging said keeper for releasing said means, means for moving said bolt when released into operative relation with said keeper, a member movable within said bolt and disposed transversely thereof for engaging said keeper to prevent retraction of 95 said bolt, means for changing the relative positions of said member and bolt, and means for retracting said bolt.

10. A lock comprising a casing, a bolt reciprocal horizontally in said casing, a keeper, means for holding said bolt retracted, means engaging said keeper for releasing said means, automatic means for moving said bolt when released into operative relation with said keeper, a member within said bolt and movable vertically to engage said keeper and prevent retraction of said bolt, means for moving said member from engagement with said keeper, and means for 105 retracting said bolt.

11. A lock comprising a casing, a bolt movable in said casing, a keeper, means for holding said bolt retracted, means engaging said keeper for releasing said means, a 110 member mounted on said bolt for engaging said keeper to prevent retraction of said bolt, means for removing said member from its engaging position, means for subsequently retracting said bolt, and means for 120 projecting said bolt and said member.

12. A lock comprising a casing, a bolt movable within said casing, an external member, means for holding said bolt retracted, means engaging said external member 125 for releasing said means, means for moving said bolt when released into operative relation to said external member, a movable member carried by said bolt and movable automatically relative thereto for engage- 130

ment with said external member to prevent a retraction of said bolt, and means for sequentially actuating said member and bolt to return the member and bolt to position within the lock casing.

13. A lock comprising a casing, a bolt mounted within said casing and adapted to be projected therefrom, means for holding the bolt retracted, means for automatically releasing said means, an interlocking bar cooperating with said bolt when fully projected, and automatic means for projecting said bolt and for causing the operation of said bar.

14. A lock comprising a casing, a bolt movable in said casing, a keeper, means for holding said bolt retracted, means for automatically releasing said means, an interlocking bar adapted to engage said keeper and to cooperate with said bolt to prevent the latter from being separated from said keeper under the action of a jimmy, and means for automatically projecting said bolt and operating said bar.

15. A lock comprising a casing, a bolt movable in said casing, a keeper, means for holding said bolt retracted, means engaging said keeper for releasing said means, an interlocking member cooperating with said bolt and keeper to prevent separation of said bolt from said keeper, and means for automatically projecting said bolt.

16. A lock comprising a casing, a bolt movable in said casing, an interlocking member, a keeper cooperating with said bolt and member, automatic means for projecting said bolt and member, and means permitting manual projection of said bolt and member.

17. A lock comprising a casing, a bolt movable in said casing, means for holding said bolt retracted, means for automatically releasing said means, automatic means to project said bolt, an interlocking member, a guard adapted to be engaged by said bolt and member, and automatic means for projecting said member.

18. A lock comprising a casing, a guard, a bolt and an interlocking bar mounted within said casing, means for holding said bolt retracted, means engaging said guard for releasing said means, automatic means to project said bolt and to actuate said bar to engage said bolt and said guard.

19. A lock comprising a casing, a guard, a bolt slidably mounted within said casing, means for holding said bolt retracted, means engaging said guard for releasing said means, automatic means for projecting said bolt, an interlocking member, and means for automatically actuating said member to engage said bolt and said guard.

20. A lock comprising a casing, a bolt mounted within said casing, means for holding said bolt retracted, means for automatically

releasing said means, a key cylinder, and automatic and manual means to project said bolt.

21. A lock comprising a casing, a bolt 70 slidably within said casing, means for holding said bolt retracted, means for automatically releasing said means, an interlocking member movable within said bolt, and resilient means for actuating said bolt and member.

22. A lock comprising a casing, a bolt 75 slidably mounted within said casing, an interlocking member movable within said bolt, resilient means for actuating said bolt and said member, a tumbler for holding said interlocking member in its locked position and a tumbler to hold said member in its unlocked position.

23. A lock comprising a casing, a keeper, 80 a bolt mounted within said casing, means for holding said bolt retracted, means engaging said keeper for releasing said means, means for automatically projecting said bolt when released, an interlocking member 85 cooperating with said keeper, and tumblers to hold said interlocking bolt in its locked and unlocked positions.

24. A lock comprising a casing, a bolt 90 mounted within said casing, means for holding said bolt retracted, means for automatically releasing said means, means for automatically projecting said bolt when released, an interlocking member associated with said bolt, and a locking tumbler for said member.

25. A lock comprising a casing, a bolt 100 mounted within said casing, means for holding said bolt retracted, means for automatically releasing said means, means for automatically projecting said bolt when released, an interlocking member associated 105 with said bolt, and an unlocking tumbler cooperating with said member.

26. A lock comprising a casing, a bolt 110 mounted within said casing, means for holding said bolt retracted, means for automatically releasing said means, means for automatically projecting said bolt when released, an interlocking member within said casing, a tumbler engaging said bolt and interlocking member, and a lock barrel having means 115 to actuate said tumbler.

27. A lock comprising a casing, a bolt and interlocking member within said casing, means for holding said bolt retracted, means for automatically releasing said means, 120 means for projecting said bolt when released, a guard, an interlocking tumbler for said member, and a lock barrel having means for operating said tumbler.

28. A lock comprising a casing, a bolt and 125 interlocking member within said casing, means for holding said bolt retracted, means for automatically releasing said means, means to project said bolt when released, means to retract said bolt, an interlocking 130

tumbler, and a lock barrel having means for moving said interlocking tumbler.

29. A lock comprising a casing, a bolt, an interlocking member within said bolt, means for holding said bolt retracted, means for automatically releasing said means, means for projecting said bolt when released, an interlocking tumbler for said member, a lock barrel having means to move said tumbler, and means for retracting said bolt.

30. A lock comprising a casing, a key cylinder extending into said casing, a bolt within said casing, a lock barrel journaled in said casing, means within said casing to permit the operation of said bolt by said barrel, cooperating means between said barrel and said key cylinder, said cooperating means being normally detached from said key cylinder.

20 31. A lock comprising a casing, a lock barrel fitted to said casing and having a gear wheel, an operating arm having a lost motion connection with said lock barrel, and means to return said arm to its initial position.

32. A lock comprising a casing, a slidable bolt within said casing, means to hold said bolt retracted, an automatic releaser for said means, means to hold said bolt inoperative, a key cylinder, and means within said casing to permit the operation of said bolt by said key cylinder.

33. A lock comprising a casing, a slidable bolt and interlocking member movable within said casing, said member being movable within said bolt, resilient members for actuating said bolt and said member, a tumbler for holding said bolt retracted, and means for automatically releasing said tumbler.

40 34. A lock comprising a casing, a bolt and interlocking member movable within said casing, a resilient means for actuating said bolt and said member, a tumbler to hold said interlocking member in its locked position, a tumbler to hold said interlocking member in its unlocked position, a tumbler for holding said bolt retracted, and a releaser for said last-mentioned tumbler.

35. A lock of the mortise type comprising a casing, a bolt adapted to be projected from said casing, an interlocking member carried by said bolt and adapted to be projected therewith, means for operating said bolt and interlocking member, means for locking said bolt in its projected position, a screw cylinder adapted to be secured in said casing and normally disengaged from said bolt, means carried by said screw cylinder and eccentrically disposed with respect to the means for operating said bolt, and a removable cover face plate for said casing.

60 36. A lock comprising a casing, a bolt and interlocking member within said casing, means to automatically project said bolt, means to retract said bolt, an interlocking

tumbler for said member, a lock barrel having means to move said tumbler, means for actuating said member, and a latch.

37. A lock comprising a casing, a carrier bolt mounted within said casing, automatic means for projecting said bolt, an auxiliary bolt carried by said carrier bolt, and a key cylinder associated with said carrier bolt, whereby said carrier bolt may be manually retracted.

70 38. A lock comprising a casing, a bolt slidably mounted within said casing for projection therefrom, means for holding said bolt retracted, means for automatically releasing said means, and a lost-motion releasing means for said bolt.

75 39. A lock comprising a casing, a bolt slidably mounted within said casing, an auxiliary bolt carried by said slidable bolt, means for holding said slidable bolt retracted, a member for releasing said slidable bolt, means to project said bolt, and means to render said releaser means inoperative.

80 40. A lock casing of the mortise type, an automatic bolt slidable within said casing, means within said casing to actuate said bolt, and a key cylinder extending into said casing to cooperate with said means, said key cylinder being normally detached from said actuating means.

85 41. A lock casing, an automatic bolt slidable within said casing, an auxiliary bolt carried by said automatic bolt, means to hold said automatic bolt inoperative, and a latch.

90 42. A lock casing, an automatic bolt slidable within said casing, a tumbler to hold said bolt retracted, a releaser for said tumbler, means disposed between the latch and said bolt to hold said bolt inoperative, and a latch.

95 43. A lock casing of the mortise type, an automatic bolt slidable within said casing, means within said casing to actuate said bolt, a key cylinder extending into said casing to cooperate with said means, said key cylinder being normally detached from said actuating means, a removable cover face plate for said casing, means operable from the face of the lock to hold said bolt inoperative, and a latch.

100 44. A lock comprising a casing, a dead bolt, means to project said bolt, and a member mounted on said bolt within the casing to automatically hold said bolt in its projected position.

105 45. A lock comprising a casing, an automatic bolt slidable within said casing, means to hold said bolt inoperative, a latch, means to project and to retract said latch, means to return the latch retractive means to initial position, and a key cylinder to actuate the bolt.

110 46. A lock comprising a casing, a bolt, means to project said bolt, means to retract said bolt, a member carried by said bolt and

- adapted to interlock with a keeper, a latch, and means to project and to retract said latch.
47. A lock comprising a casing, a bolt
5 adapted to be projected from said casing, means for holding said bolt retracted, means for automatically releasing said means, means for automatically projecting said bolt when released, means carried by said bolt
10 adapted to be projected therefrom when fully projected into engagement with a keeper, and means for locking said means in its operative and inoperative positions.
48. A lock comprising a casing, a bolt
15 adapted to be projected from said casing, means for holding said bolt retracted, means for automatically releasing said means, means for automatically projecting said bolt from said casing in one direction and then
20 to move the same at right angles thereto to engage a guard.
49. A lock comprising a casing, a bolt adapted to be automatically projected from said casing, means for holding said bolt re-
25 tracted, means for automatically releasing said means, means including a cam for projecting said bolt from said casing and then to move the same at right angles thereto.
50. An automatic mortise lock having a
30 casing and a key cylinder screwed therein, and a bolt adapted to be operated by said key cylinder, said casing having means for automatically holding said bolt in its projected position.
51. An automatic mortise lock having a
35 casing and a key cylinder screwed therein, a latch, and a bolt adapted to be operated by said key cylinder.
52. A lock comprising a casing, a bolt
40 adapted to be projected from said casing, a locking tumbler to hold said bolt projected, and lost motion means including a gear member for operating said tumbler and said bolt.
53. In a lock for a door, a guard, a lock
45 casing, a member adapted to be projected from said casing, said member having means for interlocking with said guard, said means being supported by said member at a plural-
50 ity of points within the guard when said member and means are engaging the guard,
- and a key cylinder extending into said casing to operate said bolt, said key cylinder and its connection to said bolt being normally detached. 55
54. In a lock for a door, a guard, a lock casing, a member adapted to be projected from said casing, said member having means for interlocking with said guard, said means being supported by said member at a plural-
60 ity of points within the guard when said member and means are engaging the guard, and a key cylinder screwed into said casing. 65
55. In a lock for a door, a guard, a lock casing, a member adapted to be projected from said casing, said member having means for interlocking with said guard, said means being supported by said member at a plural-
70 ity of points, and a key cylinder screwed into said casing and extending through said door. 75
56. In a lock for a door, a guard, a lock casing, a member adapted to be projected from said casing, means for projecting said member from said casing, said member having means for interlocking with said guard, said means being supported by said member at a plural-
75 ity of points, and a key cylinder screwed into said casing and cooperating with the means for projecting said member.
57. In a lock for a door, a guard, a lock
80 casing, a member adapted to be projected from said casing, said member having means for interlocking with said guard, said means being supported by said member at a plural-
85 ity of points within the guard when said member and means are engaging the guard, a key cylinder extending into said casing to operate said member, said key cylinder and its connection to said member being normally detached, a latch, and means to pro-
ject and to retract said latch. 90
58. A lock comprising a casing, a bolt adapted to be projected from said casing, a toothed spindle, a key cylinder lock having a key barrel and a housing therefor, said
95 housing extending into said casing, and said cylinder lock having a lost motion connection with said spindle.
- In testimony whereof, I have hereunto
subscribed my name this 26th day of No-
vember, 1923.
- CLIVE W. LANPHERE.

DISCLAIMER.

1,621,549.—*Clive W. Lamphere*, New York, N. Y. UNIVERSAL JIMMYPROOF AUTOMATIC LOCK. Patent dated March 22, 1927. Disclaimer filed October 18, 1927, by the patentee.

Hereby enters this disclaimer to that claim in said specification which is in the following words, to wit:

“ 52. A lock comprising a casing, a bolt adapted to be projected from said casing, a locking tumbler to hold said bolt projected, and lost motion means including a gear member for operating said tumbler and said bolt.”

[*Official Gazette November 8, 1927.*]
